CLAIM

The ornamental design for an inhaler, as shown and described.

DESCRIPTION

FIG. 1 is a rear, top, right side perspective view of an inhaler in accordance with the new design, shown in an open configuration;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.
